US0D1098898S

(12) **United States Design Patent** (10) **Patent No.:** **US D1,098,898 S**
(45) **Date of Patent:** **** Oct. 21, 2025**

(54) **CABLE HANGER**

(71) Applicant: **Cambria County Association for the Blind & Handicapped**, Johnstown, PA (US)

(72) Inventor: **Jason Richard Martinage**, South Fork, PA (US)

(73) Assignee: **CAMBRIA COUNTYASSOCIATION FOR THE BLIND AND HANDICAPPED**, Johnstown, PA (US)

(**) Term: **15 Years**

(21) Appl. No.: **29/991,818**

(22) Filed: **Mar. 4, 2025**

Related U.S. Application Data

(63) Continuation of application No. 29/904,653, filed on Oct. 10, 2023, now Pat. No. Des. 1,069,563.
